Right from Quincy May

Atty.

UNITED STATES PATENT OFFICE.

ISAAC E. SEXTON, OF WINCHESTER, MASSACHUSETTS.

SHEET-METAL CAN.

Application filed February 17, 1923. Serial No. 619,657.

To all whom it may concern:

Be it known that I, ISAAC E. SEXTON, a citizen of the United States, residing at Winchester, in the county of Middlesex and 5 State of Massachusetts, have invented new and useful Improvements in Sheet-Metal Cans, of which the following is a specification.

The invention is embodied in a can, and 10 a closure for the mouth thereof, of such construction that when the can is prepared for the market, the mouth is closed by two joints, one outside and the other within the mouth, the outer joint being formed by the 15 cooperation of a cap with the mouth, and the inner joint by the conjoint cooperation with the mouth of said cap and a stopper formed as an independent part.

Of the accompanying drawings forming 20 a part of this specification,—

Figure 1 is a side elevation of a portion of a can mouth, and a closure therefor.

Figure 2 is an enlarged section on line 2—2 of Figure 1.

25 Figures 3, 4, and 5 are sectional views showing separately the parts shown assembled by Figure 2.

Figure 6 is a sectional view, showing the 30 cap and the stopper assembled preparatory to application to the mouth.

Figure 7 is a sectional view, showing the mouth and the stopper after the removal of the cap.

Figure 8 is a sectional view, showing the 35 mouth and the cap without the stopper.

Figure 9 is a sectional view, illustrating the operation of frictionally engaging the cap with the stopper.

Figure 10 is a view similar to Figure 2 40 showing the stopper provided with a marginal annular lip.

Figures 11 and 12 are views similar, respectively, to Figures 6 and 7, showing the stopper as in Figure 10.

45 The same reference characters indicate the same parts in all the figures.

In the drawings, 12 represents the tubular mouth of a sheet metal can. A portion 13 of the internal surface of the mouth forms 50 an annular internal stopper seat. A portion 14 of the mouth forms an annular external cap flange seat. An intermediate portion 15 of the mouth forms an annular end shoulder between the seats 13 and 14.

55 The mouth and the flange portion of the cap hereinafter described, are preferably

constructed as shown by my Patent No. 1,419,314, dated June 13, 1922. A sheet metal stopper, composed of a circular head 16, and a tapering upstanding annular flange 60 17, is adapted to cooperate with the internal seat 13, in forming an inner joint closing the mouth, the taper and diameter of the flange 17 being such that when the stopper is forced into the neck, the flange is wedged 65 firmly in the seat 13, and forms a practically fluid-tight joint.

A sheet metal cap is provided, which is adapted to transmit pressure to the stopper to wedge the same in the neck, and is also 70 adapted to frictionally engage the outer seat 14, to form an outer joint. Said cap includes an annular portion 19, which coincides with the end shoulder 15, an annular flange 20, projecting downward from the 75 outer part of the portion 19, and adapted to frictionally engage the outer seat 14, and a central boss projecting downward from the inner part of the portion 19, and composed of a circular head portion 21, and a 80 tapered annular wall portion 22, inserted in and conforming to the taper of the stopper flange 17.

The wall portion 22 and flange 17 are frictionally engaged with each other, so that before the application of the closure to the mouth, the cap and stopper are adapted to be handled and applied to the mouth as a single part. The stopper flange may be initially formed with a taper which is less than 85 that of the wall portion 22, of the boss, as shown by Figure 9, so that the operation of forcing the boss into the stopper slightly expands the stopper flange and causes it to engage the wall portion 22, with sufficient 90 firmness to hold the parts assembled for manipulation and application to the mouth, and permit the separation of the cap from the stopper by force exerted as described in my former patent, to remove the cap from 95 the mouth.

It will now be seen that when the assembled cap and stopper are applied to the mouth, and downward pressure is exerted on the cap, the cap flange 20, and the stopper flange 17, simultaneously engage the external seat 14, and the internal seat 13, respectively, and form the inner and outer joints. The pressure transmitted through the cap to the stopper flange wedges the 105 flange in the internal seat so firmly that the frictional engagement between the stopper 110

and the mouth is stronger than that between the cap and the stopper, so that the removal of the cap leaves the stopper in place, as shown by Figure 7. Provision is therefore made for opening the mouth by two operations. The stopper may be rendered inoperative in any suitable manner, after the removal of the cap, as by cutting an opening in the head portion 16, of sufficient size to 10 constitute a pouring outlet, or to permit the insertion of a hook, whereby the stopper may be pulled out.

When the parts are assembled, as shown by Figure 2, the mouth is tightly sealed, 15 the wedging action of the stopper flange 17, on the internal seat 13 causing a close and accurate conformation of these sheet metal parts to each other.

When the stopper has been removed or 20 rendered inoperative, the mouth may be again closed, although possibly not so tightly as before, by engaging the cap flange with the external seat 14, as shown by Figure 8.

As shown by Figures 10, 11 and 12, the 25 stopper flange 17 may be provided with an annular lip 18, adapted to be seated on the neck 15, under the annular portion 19 of the cap. The object of the lip 18 is to enable the stopper to be conveniently removed by a prying tool inserted between its under side and the neck 15, when the cap is removed. When the lip 18 is employed, the annular portion 19 of the cap bears on the lip instead of on the neck 15.

35 The lower portion of the cap flange 20 may be flared outward, so that it is separated by a crevice 24 from the seat 14, as shown by Figure 10. The bearing of the cap flange on the seat is therefore limited, 40 so that, although a tight joint is formed, the cap may be more easily removed from its seat, than when it has the extended bearing shown by Figures 2 and 8.

The wall 22 of the cap boss may be narrower than the stopper flange, as shown by 45 Figures 10 and 11, so that the bearing of the wall on the stopper flange is narrower than the width of the said flange. The wall 22 is therefore separable from the flange 17

more easily than said flange is separable 50 from the internal seat 13.

I claim:

1. A sheet-metal can comprising, in combination, a tubular mouth having an annular internal stopper seat, an annular external cap flange seat, and an annular end shoulder between said seats; a stopper having a circular head and a tapering upstanding flange, adapted to be wedged into said stopper seat, and form therewith an inner 60 joint; and a cap having an annular face, coinciding with said end shoulder, an annular flange projecting downward from the outer portion of the annular face, and a central boss projecting downward from the inner 65 portion of said face, said boss including a tapering annular wall inserted in and conforming to the tapering stopper flange and separably engaged therewith, so that the cap and stopper are applicable as a unit to 70 the mouth, and are movable by pressure exerted on the cap to frictionally engage the stopper flange with the stopper seat, thus forming an inner joint, and frictionally engage the cap flange with the said external 75 seat, thus forming an outer joint, the arrangement being such that when the cap is removed from the mouth, the stopper remains therein.

2. A sheet-metal can embodying the combination specified by claim 1, the said stopper being provided with an annular lip, adapted to abut against said end shoulder, and to engage a prying tool inserted between the lip and the shoulder.

3. A sheet-metal can embodying the combination specified by claim 1, the said cap flange being flared outward at its lower portion to limit its bearing on said external seat.

4. A sheet-metal can embodying the combination specified by claim 1, the said annular boss wall being narrower than the said stopper flange, to facilitate the separation of the wall from the flange.

In testimony whereof I have affixed my signature.

ISAAC E. SEXTON.
